GRINDING MACHINE

Harry G. Day, Columbia Heights Station, Minn.

Application May 17, 1933, Serial No. 671,491

10 Claims. (Cl. 83—11)

This invention relates to a grinder which can be employed to reduce or pulverize various materials, but which has been designed to be more especially useful to reduce or pulverize grain.

5 A broad object of the invention is to provide a grinder or grinding machine of the closed system type wherein will be incorporated various novel and improved features and characteristics of construction designed to render the present 10 grinder or grinding machine an improvement generally over more or less similar structures heretofore known.

A more explicitly stated object is to provide 15 a grinder or grinding machine including closed system conveyors for moving a column of air and ground material transported by said moving column of air, wherein said conveyors will be so constructed and related to each other, and to the grinding element, the fan or blower and 20 the collector of the grinder or grinding machine, that the reducing or pulverizing action upon the material being ground and the conveying of the ground material to the receiver therefor will be accomplished in really ideal manner, without 25 liability of loss of any of the ground material, in the form of dust, or otherwise, from the grinder or grinding machine or any of the conveyors thereof.

A further explicitly stated object is to provide 30 a grinder or grinding machine including closed system conveyors for the purpose and of the construction and having the relation to each other and to the grinding element, the fan or blower and the collector of the grinder or grinding 35 machine as set forth, wherein all of the component parts of said grinder or grinding machine have been designed with the idea in view of nicely controlling the amount, velocity and pressure of air of the moving column at the 40 various locations in the grinder or grinding machine, and especially at and adjacent to the grinding element, the fan or blower, the collector, and the receiver for the ground material, to thus balance the grinding and air blowing 45 condition in said grinder or grinding machine and reduce to a minimum the possibility of loss of the ground material, even in the form of dust.

50 And a further explicitly stated object is to provide a closed system grinder or grinding machine, the air and ground material transporting conveyors of which are so constructed and related to each other, and to all other component parts of the grinder or grinding machine, that 55 tendency of air to enter said system or become

removed therefrom is reduced to a minimum, once the grinder or grinding machine is set in operation.

With the above objects in view, as well as others which will appear as the specification 5 proceeds, the invention comprises the construction, arrangement and combination of parts as now to be fully described and as hereinafter to be specifically claimed, it being understood that the disclosure herein is merely illustrative and 10 intended in no way in a limiting sense, changes in details of construction and arrangement of parts being permissible so long as within the spirit of the invention and the scope of the claims which follow.

15 In the accompanying drawing forming a part of this specification,

Fig. 1 is an elevational view, partially in section and partially broken away, of a grinder or grinding machine in which the features of 20 the invention are incorporated;

Fig. 2 is a fragmentary elevational view of the grinder or grinding machine, as seen from the right in Fig. 1; and

Fig. 3 is a fragmentary plan view, as seen from 25 the top of the sheet in Fig. 1.

With respect to the drawing and the numerals of reference thereon, 10 denotes a casing for the grinding element of the grinder or grinding machine, and 11 indicates a casing for the fan 30 or blower. As shown, said grinding element and said fan or blower are mounted adjacent each other upon a horizontal shaft 12. Said grinding element and said fan or blower are fixed to the shaft 12, and a pulley 13, also fixed to said shaft, 35 may be suitably driven to propel the grinding element and fan or blower, although these may be propelled in any other suitable manner.

The grinding element casing 10 includes an open mouth 14 above the grinding element, and 40 a bin spout or outlet, represented 15, leading from a supply of grain or other material to be reduced or pulverized, may enter directly into said mouth 14 of said casing 10.

The grinding element casing 10 includes a feed 45 device 16 for grain or other material to be ground, and said feed device is actuated from the shaft 12 by means of a belt 17 riding over a pulley 18 upon said shaft 12.

A collector 19 for reduced or pulverized grain, 50 or other reduced or pulverized material, is situated at elevation above the grinding element and the fan or blower, at one side of said element and fan or blower as disclosed, and a receiver 20 for said reduced or pulverized grain, 55

or other material, is arranged directly below said collector. As shown, the lower portion 21 of said collector 19 is tapered to tightly fit into an opening in the upper wall of the receiver 20, as indicated at 22, whereby the collector feeds directly into the receiver, as will be obvious. The receiver 20 can be a completely closed storage tank, except for the opening therein leading from the collector. As disclosed, the lower portion of the receiver is also tapered, as denoted at 23, and said tapered portion 23 merges into a downwardly extending outlet pipe 24, of cross-sectional area considerably less than that of the receiver. The lower portion of said pipe 24 is fitted with a horizontal slide valve 25 which can be completely closed, as shown in Fig. 1 of the drawing, or can be opened to allow passage by gravity of ground grain or other ground material into containers therefor, such, for example, as the sack 26 placed upon the table 27, beneath the pipe 24.

The grinder or grinding machine includes a conveyor 28 for reduced or pulverized grain or other material and air leading upwardly from the fan or blower casing 11 to the collector 19, and a conveyor 29 for air leading downwardly from said collector to the grinding element casing to either side of the grinding element and to said fan or blower casing, which conveyors 28 and 29 are so constructed and related to each other and to said grinding element, fan or blower and collector that the reducing or pulverizing action upon the material being ground and the conveying of the ground material to the collector, and thence by gravity to the receiver, is accomplished without liability of loss of ground material. That is to say, all of the component parts of the grinder or grinding machine, including the grinding element and its casing, the fan or blower and its casing, the collector, the receiver, and the conveyors 28 and 29, have been designed and constructed and related to each other with the idea in view of nicely controlling the amount, velocity and pressure of air at the several different locations in the grinder or grinding machine, to thereby not only reduce to a minimum the tendency of air to enter or become removed from the grinding system of the machine and thus preclude the loss of ground material, but also to nicely balance the grinding and air blowing condition in the grinder or grinding machine.

The conveyor 28 is vertically disposed as shown, and includes an upper horizontal portion 30 which tangentially and tightly enters the upper portion of the vertical wall of the collector 19, as indicated at 31.

The conveyor 29 includes an upper bent or curved portion 32 tightly fitted into the upper wall of the collector 19 and leading therefrom, a vertical portion 33 extending downwardly from said portion 32, a branch 34 which as disclosed extends obliquely downwardly from said vertical portion 33 and is tightly fitted into the grinding element casing 10 above the grinding element, and a branch 35 extending horizontally from said vertical portion 33 past the lower portion of the grinding element casing 10 and then bent or curved, as at 36, and tightly fitted into the fan or blower casing 11. The grinding element casing 10 is tightly fitted into and communicates with the branch 35 of the conveyor 29 at the side of the grinding element which is opposite the branch 34, as clearly indicated at 37 in Fig. 1.

As will be evident, when the shaft 12 is driven 75 to operate the grinding element and the fan

or blower, air is fed to the grinding element casing and to the fan or blower casing, past the outlet 37 of said grinding element casing, through the conveyor 29 and the branches 34 and 35 thereof. The reduced or pulverized material, 5 which was fed into the casing 10 through the mouth 14 thereof, is carried by the air past the outlet 37 and through the branch 35 and its curved portion 36 to the fan or blower casing. The mixed air and ground material are then 10 fed upwardly through the conveyor 28 and into the collector 19, where said air and ground material separate, the ground material falling by gravity through the collector 19 into the receiver 20, and the air, with some lighter particles of 15 ground material, enters the curved upper portion 32 of the conveyor 29 and then passes downwardly through said conveyor 29 to repeat the cycle as described. Both the air which passes from the vertical portion 33 of the conveyor 29 20 through the branch 34 directly into the casing 10 and the air which passes from said vertical portion through the branch 35 past the outlet 37 cooperate to carry the ground material to the fan or blower, as will be evident. 25

It will be noted that the portion of the conveyor 29 attached to the collector 19 and extending to position below the branch 34 is of considerably greater cross-sectional area than is the conveyor 28 leading from the fan or blower 30 to said collector 19. For example, the mentioned portion of the conveyor 29 may desirably be, say, ten inches in diameter when the conveyor 28 is six inches in diameter, so that the velocity and pressure of air in the portion of said conveyor 29 extending from the collector 19 to the branch 34, or below said branch, will be relatively lower than the velocity and pressure of air in the conveyor 28, as will be understood. Thus the air can be led easily from the vertical 40 portion 33 of the conveyor 29 into the branches 34 and 35, respectively, which branches may desirably each be of about the same cross-sectional area as is the conveyor 28. 45

While the velocity and pressure of air in the portion of the conveyor 29 leading from the collector 19 down to the location of the outlet of the branch 34, and particularly adjacent said outlet, is relatively lower than the velocity and pressure of air in the conveyor 28, the amount 50 of air in said mentioned portion of the conveyor 29 is always of sufficient capacity so that each of the branches 34 and 35 can be supplied a requisite quantity of air during the operation of the grinding element and the fan or blower. 55

More specifically stated, the fan or blower builds up in the conveyor 28, along the whole of the length thereof, a velocity and pressure of air which becomes approximately fixed shortly after the fan or blower is set in operation, and thereafter remains substantially fixed as long as the grinding operation continues. Evidently, the moving content in said conveyor 28 consists at all times of a considerable quantity of ground material in addition to the air. When the ground material becomes separated from the air in the collector 19, the pressure of air entering the conveyor 29 is decreased, and air passing downwardly through the portion 33 of the conveyor 29 is under pressure lower than the pressure in 70 the conveyor 28 and travels at slower velocity than the content of said conveyor 28. The air traveling at slow velocity and under low pressure and directly accessible to the branch 34, allows for easy leading of the air through said 75

branch 34 into the grinder element casing, which so takes all of the air necessary to the grinding operation as this progresses from time to time. The remainder of the air passing through the conveyor 29 goes to the fan or blower through the branch 35, past the outlet 37 from the grinding element casing 10, and the branches 34 and 35 cooperate to keep the air pressure in the upper portion of the conveyor 29 from rising 10 to too high a pressure.

In order that the grinding and air blowing condition in the grinder or grinding machine may be properly balanced, it is essential that each of the branches 34 and 35 be of sufficient cross-sectional area so that either will have capacity to transport the major part of the air passing through the upper portion of the conveyor 29 to either side of the grinder proper. Were said upper portion of the conveyor 29 of 20 cross-sectional area as small as, or not much greater than, the cross-sectional area of each of the conveyor 28, the branch 34, and the branch 35, there would obviously be no capacity for feeding any considerable quantity of air through 25 said branch 34, for the reason that by far the greater part of the air traveling at relatively high velocity would pass through the branch 35 rather than through the branch 34, due both to the fact that the fast traveling, small amount 30 of air is not easily leadable, and the further fact that the grinding operation itself sets up a certain amount of resistance to the air. And were the condition altered to reduce the amount of air which could possibly travel through the 35 branch 35, there would then be, under certain working conditions, an unbalancing of the grinding and air blowing condition, because at times when the grinder proper gets choked, or partially choked, there must be full capacity 40 for all of the air to travel through the branch 35 and past the outlet 37. Upon the grinder proper becoming choked, or partially choked, there is in the machine capacity for passage of all of, or the greater part of, the air through 45 the branch 35 and past the outlet 37, where said air creates a suction action upon the grinder proper. In short, there is capacity for passage of air in considerable quantity through the grinder proper, as well as capacity for passage 50 of all of the air traveling through the upper portion of the conveyor 29 through the branch 35, and the component parts of the grinder or grinding machine are so constructed and related to each other that the air travel through 55 said branches 34 and 35 is automatically varied and controlled as the machine operates, to insure that the grinding and the air blowing condition will at all times remain properly balanced.

The grinder or grinding machine includes an 60 air bleeder pipe 38 which leads upwardly from the upper wall of the receiver 20, is bent or curved horizontally and then obliquely downwardly, and is tightly attached, as at 39, to the vertical portion 33 of the conveyor 29, at location above the branch 34. The evident purpose of the pipe 38 is to carry any traces of air which may enter the receiver 20 with ground grain, or other ground material, directly into the conveyor 29.

70 It will be seen that the flow of air in the grinder or grinding machine is continuous, and the same air. There is no tendency for air to enter the casing 10 with the grain to be ground, principally for the reason that the full need for 75 air in the grinder proper is adequately supplied

through the branch 34, as already set forth. There is, also, no air outlet to carry particles or dust away from the ground material. The only outlet from the machine is the pipe 24, which can, as before stated, be completely closed. And 5 even when the pipe 24 is opened, the ground grain, or other ground material, passing downwardly therethrough provides a seal against the passage of air upwardly through said pipe 24 to the receiver. 10

What is claimed is:

1. A grinding machine comprising a grinding element, a casing for said grinding element, a blower, a casing for said blower, a collector for ground material above said blower, a conveyor 15 for air and ground material leading upwardly from said blower casing to said collector, and a conveyor for air leading downwardly from said collector and including branches one of which feeds into said grinding element casing and the 20 other of which feeds into said blower casing at the side thereof opposite said first mentioned conveyor, said grinding element casing opening to said branch feeding into said blower casing at the side of said grinding element opposite said branch feeding into said grinding element casing, and the portion of said air conveyor between said collector and said branch feeding into said grinding element casing being of sufficiently great 25 capacity to transport air at velocity and under 30 pressure lower than the velocity at which and the pressure under which air and ground material are transported by said air and ground material conveyor.

2. A grinding machine comprising a grinding 35 element, a casing for said grinding element, a blower, a casing for said blower, means for operating said grinding element and said blower, a collector for ground material, a conveyor for air and ground material leading from said blower 40 casing to said collector, and a conveyor for air leading from said collector and including branches one of which feeds into said grinding element casing and the other of which feeds into said blower casing at the side thereof opposite said first mentioned conveyor, said grinding element casing opening to said branch feeding into said blower casing at the side of said grinding element opposite said branch feeding into said 45 grinding element casing, and the portion of said air conveyor between said collector and said branch feeding into said grinding element casing being of greater cross-sectional area than the cross-sectional area of said air and ground material conveyor. 50

3. A grinding machine comprising a grinding element, a casing for said grinding element, a blower, a casing for said blower, means for operating said grinding element and said blower, a collector for ground material, a conveyor for air and ground material leading from said blower casing to said collector, and a conveyor for air leading from said collector and including branches one of which feeds into said grinding element casing at the side thereof where material to be ground enters said casing and the other of which feeds into said blower casing at the side thereof opposite said first mentioned conveyor, the side of said grinding element casing where 60 ground material departs opening to said branch feeding into said blower casing, said conveyor for air and ground material, and said branches, respectively, being of approximately equal cross-sectional area, and the portion of said conveyor 65 70

75

for air between said collector and said branches being of considerably greater cross-sectional area than the cross-sectional area of said conveyor for air and ground material, or either of said 5 branches, for the purpose described.

4. The combination as specified in claim 3, wherein said portion of said conveyor for air between said collector and said branches is of cross-sectional area at least one and one-half 10 times as great as the cross-sectional area of said conveyor for air and ground material, or either of said branches.

5. A grinding machine comprising a grinding element, a casing for said grinding element, a blower, a casing for said blower, a collector for ground material, a conveyor for air and ground material between said blower casing and said collector, and a conveyor for air between said 15 collector and said grinding element casing and 20 said blower casing, said last mentioned conveyor including a branch leading into and a branch leading away from said grinding element casing, and also including a portion thereof adjacent 25 said branch leading into said grinding element casing of capacity necessitating air to pass through said portion at relatively lower pressure than air and ground material pass through said 30 first mentioned conveyor.

6. A grinding machine comprising a grinding element, a casing for said grinding element, a blower, a casing for said blower, a collector for ground material, a conveyor for air and ground material leading from said blower casing to said 35 collector, and a conveyor for air leading from 40 said collector and including a branch leading into said grinding element casing and a branch leading into said blower casing, a portion of said last mentioned conveyor adjacent said branch leading into said grinding element casing being 45 of capacity necessitating air to travel therein at relatively lower velocity and pressure than air and ground material travel through said first mentioned conveyor.

7. A grinding machine comprising a grinding element, a casing for said grinding element, a blower, a casing for said blower, a collector for ground material, a conveyor for air and ground material between said blower casing and said collector, a conveying passage for air leading from 50 said collector and of sufficient capacity to cause air to travel therein at velocity less than that at which air and ground material travel in said conveyor between said blower and collector, a branch passage leading from said conveying passage into said grinding element casing at the side thereof which receives material to be ground, and a branch passage leading from said conveying passage to said blower casing, the side of said 55 grinding element casing where ground material departs communicating with said last mentioned branch passage, each of said branch passages having capacity to transport a requisite amount of air from said conveying passage to 60 said grinding element casing and said blower casing, respectively, to balance the grinding condition in said grinding element casing, and said branch passages cooperating with each other to keep the air pressure uniform in said conveying passage.

8. A grinding machine comprising a grinding element, a casing for said grinding element, a blower, a casing for said blower, a collector for ground material, a conveyor for air and ground material leading from said blower casing to said 65 collector, and a conveyor for air leading from said

collector and including branches one of which feeds into said grinding element casing at the inlet side thereof and the other of which feeds into said blower casing, said grinding element casing opening at the outlet side thereof to said branch feeding into said blower casing, a portion of said conveyor for air between said collector and said branch feeding into said grinding element casing having area to transport air at relatively lower velocity than the velocity at which air and ground material are transported by said conveyor for air and ground material, and each of said branches being related to said mentioned portion of the conveyor for air and having capacity to transport a requisite amount of air from 10 said portion to the grinding element casing and the blower casing, respectively, to at all times balance the grinding condition in the grinding element casing and thus reduce to a minimum the possibility of loss of ground material. 15

9. A grinding machine comprising a grinding element, a casing for said grinding element, a blower, a casing for said blower, a collector for ground material, a conveyor for air and ground material between said blower casing and said collector, a conveying passage for air leading from 20 said collector and of sufficient capacity to cause air to travel therein at velocity less than that at which air and ground material travel in said conveyor between said blower and said collector, a branch passage leading from said conveying passage into said grinding element casing at the side thereof which receives material to be ground, and a branch passage leading from said conveying passage to said blower casing, the side of 25 said grinding element casing where ground material departs communicating with said last mentioned branch passage, each of said branch passages having capacity to transport a requisite amount of air from said conveying passage to 30 said grinding element casing and said blower casing, respectively, to balance the grinding condition in said grinding element casing, and said branch passages cooperating with each other to keep the air pressure uniform in said conveying passage. 35

10. A grinding machine comprising a grinding element, a casing for said grinding element, a blower, a casing for said blower, a collector for ground material, a conveyor for air and ground material between said blower casing and said collector, and a conveyor for air between said 50 collector and said grinding element casing and said blower casing, said last mentioned conveyor including a branch leading into said grinding element casing and a branch leading into said blower casing at a side thereof opposite said first mentioned conveyor, said grinding element casing opening to said branch leading into said blower casing at the side of said grinding element opposite said branch leading into said grinding element casing, and a portion of said conveyor for air adjacent said branches leading into said grinding element casing and said blower casing, respectively, being of capacity necessitating air to pass through said portion at relatively lower velocity and pressure than air and ground material travel through said first mentioned conveyor. 60
